(57) **CLAIM**

The ornamental design for a charging flap for a vehicle, as shown and described.

DESCRIPTION

FIG. 1 is a front left perspective view of a charging flap for a vehicle according to the present invention.

FIG. 2 is a front right perspective view of the charging flap shown in FIG. 1.

FIG. 3 is a rear right quarter view thereof.

FIG. 4 is a rear left perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a front view of the charging flap shown in FIGS. 1-10, with the charging flap mounted on a vehicle, and the rest of the vehicle shown in de-emphasized and half-tone portions so as to illustrate environmental structure. These portions form no part of the claimed invention. More particularly, in FIG. 11, the inventive charging flap is shown within the broken line, and the elements shown outside the broken line form no part of the claimed invention, but are instead included to show environmental aspects thereof.
